CLAIM

I claim the ornamental design for a regenerative media filter display panel with graphical user interface, as shown and described.

DESCRIPTION

FIG. 1 is a plan view of a regenerative media filter display panel with graphical user interface in accordance with a first embodiment of the invention;

FIG. 2 is a plan view of a regenerative media filter display panel with graphical user interface in accordance with a second embodiment of the invention;

FIG. 3 is a plan view of a regenerative media filter display panel with graphical user interface in accordance with a third embodiment of the invention; and,

FIG. 4 is a front view of a regenerative media filter showing a regenerative media filter display panel with graphical user interface in accordance with a fourth embodiment of the invention.

The outermost solid-line rectangle shown in FIGS. 1-4 illustrates the perimeter of the display panel.

The broken lines shown outside the outermost solid-line rectangle illustrate a regenerative media filter and form no part of the claimed design. The remaining broken lines illustrate portions of a graphical user interface and form no part of the claimed design.
